MANUFACTURE OF CIGARETTES

William Frederick Maitland Edwards, London,
and Rowland Frank May, Middlesex, England,
assignors to Filter Tips Limited, London, Eng-
land, a British company

Application December 20, 1934, Serial No. 758,504
In Great Britain December 23, 1933

21 Claims. (Cl. 131—39)

This invention relates to the manufacture of cigarettes and is concerned with improvements in methods of and apparatus for the production of filter tip or like composite cigarettes comprising 5 cigarettes or lengths of cigarette rod and filter tips or other mouthpiece or intermediate fillings or insertions united together by encircling bands of cork, paper or other suitable external tipping material.

10 Heretofore such cigarettes have been produced by associating the lengths to be united in intermittently movable carrying means and applying the uniting bands without axial movement of the assembled lengths.

15 The present invention has for its primary object to produce such filter tip or composite cigarettes on the continuous rod principle whereby the assembling of the lengths and the application of the uniting bands may take place while the 20 lengths are travelling forward axially with a view to facilitating the production at relatively high speed.

25 The invention is hereinafter described by way of example with reference to the accompanying drawings, in which:

Figures 1, 1a, 1b, 1c and 1d taken together represent a view in side elevation illustrating one embodiment of apparatus in accordance with the invention;

30 Figure 2 is a cross-section on the line II—II, Figure 1c;

Figure 3 is a cross-section on the line III—III, Figure 1d;

Figure 4 is a sectional view of the suction roller; 35 and

Figure 5 is a detail plan view of the plunger operating lever.

In carrying the invention into effect according to one embodiment, cigarettes, or preferably double lengths of cigarette rod, are fed by any suitable means in a continuous stream through a guide 1 and are thereby directed between co-operating pressure rollers 2, 2a, as shown in Fig. 1c. The roller 2 itself may be driven so that its peripheral speed is greater than the speed of feed of the cigarettes or lengths of cigarette rod, but preferably the roller 2 carries a belt 3 which is driven so as to move at a suitably increased speed in relation to the speed of feed of the cigarettes or lengths of cigarette rod, so that each cigarette or length is thereby accelerated away from the following cigarette or length to form an intermediate space permitting the application of a single or double length of filter tip or other mouthpiece or intermediate formation or filling.

The roller 2a may be carried by an arm 2b and rotates idly, or if desired may be driven so that its peripheral speed corresponds to that of the belt 3.

The single or double lengths of filter tip or other mouthpiece or intermediate formation may be applied by any suitable means into the spaces formed between the cigarettes or lengths of cigarette rod. In a preferred arrangement, however, an intermittently rotatable disc or drum 4 having 10 a circumferentially arranged series of bores 4a (Figure 2) is arranged so that double lengths of filter tip or other mouthpiece or intermediate formation (hereinafter referred to as "double filter tip") inserted into the bores 4a, directly or indirectly from forming mechanism or from a suitable hopper feed, are carried successively into alignment with the lengths of cigarette rod. Preferably the disc or drum 4 is disposed adjacent to the outlet side of the rollers 2, 2a so that as each length of cigarette rod is accelerated it is cause to abut the double filter tip disposed in alignment therewith and carries the same out of the respective bore 4a, and so that after the length of cigarette rod has passed through the 25 bore 4a, leaving a space between it and the succeeding length of cigarette rod, the disc or drum 4 may move to bring the next double tip into position. The double tip and length of cigarette rod issuing from the bore 4a pass between pressure rollers 5, 5a adapted to feed at the same speed as the rollers 2, 2a, the roller 5 conveniently carrying the belt 3 which is looped around rollers 6, 6a while the roller 5a mounted on an arm 5b may be idle or be driven as desired. The 30 intermittent movement of the disc or drum 4 may be effected by a cam disc 4b engaging a suitably toothed rim 4c on the disc or drum 4.

From the roller 5 the belt 3 carrying the assembled lengths of cigarette rod and double filter tips passes into a garniture 7 from which the assembled lengths are directed into a tubular guide 8, preferably having a feed roller 8a co-operating therewith, and delivered by such guide 8 to means for applying uniting bands of cork or other suitable material whereby the lengths are joined together to form a continuous rod made up of alternate lengths of cigarette rod and double filter tips and which is subsequently subdivided to produce cigarettes each containing a 50 filter tip or other insertion either at the mouthpiece end or at an intermediate position.

The belt 3 issuing from the garniture 7 is led over rollers 9, 9a, 10, 11, the roller 11 being driven through gears 11a, 11b (Figs. 1c and 2), for 55

example by means of a chain 12 engaging a sprocket 11c on spindle 12b which carries gear 11b and passing over a sprocket on spindle 12a and over a sprocket 13a on a spindle 13 upon which the cam disc 4b is mounted so that thereby the movement of the disc or drum 4 is definitely related to the travel of the belt 3.

The cork or other uniting bands may be applied by any suitable means. For example, a continuous strip 14 (Fig. 1b) of pre-gummed cork or the like may be led from a supply spool 14a and over a roller 14b, through guide 14c and between a driven feed roller 14d and pressure roller 14e, the latter being carried by a lever 14f controlled by a hand-operated cam 14g and return spring for the purpose of starting and stopping the feed of the strip 14. From the rollers 14d, 14e the strip passes over a guide roller 14h with its non-gummed side in engagement with a belt 15 looped around rollers 15a, 15b. While carried on the belt 15 around the roller 15a the gummed face of the cork or like strip is moistened by the provision of a roller 16 having a felt rim 16a dipping into a water receptacle 17 and preferably driven, as by the provision of gears 16b, 16c from a gear 18a on a cross-shaft 18. The belt 15 is perforated and a suction box 15c is arranged between the rollers 15a, 15b so that by the action of suction exerted through the perforations in the belt 15 the strip 14 is retained against the outer face of the belt and thereby directed in a straight path into engagement with a roller 19 by which the cork is applied to the assembled lengths issuing from the guide 3 and which carries the wrapping belt 20 associated with the final garniture 21. Preferably the wrapping belt 20 is of less width than the cork or like strip 14 and is received in a corresponding groove 19a in the periphery of the roller 19, the projecting rims 19e on the roller 19 being formed with apertures 19c communicating with a source of suction 19b controlled by a stationary port 19d or equivalent shut-off member (Fig. 4) in such manner that the cork is released at or about the position at which it engages the assembled lengths. A rotary knife 22 mounted on a vertical shaft 22a and driven by means of a gear 22b from a gear 18b on the shaft 18 is arranged to sever the cork strip 14 at a position intermediate the belt 15 and the roller 19. In order to keep the knife 22 clean its under face may be wiped by a felt pad 22c extending into a water container 22d. The roller 14d by which the feed of the cork 14 is governed is driven, as by means of gears 14i, 14j, 14k, 14l from a cross-shaft 14m which may be driven from the cross-shaft 18 or other convenient part. The cork or like strip 14 is thereby fed at a relatively slower speed than the peripheral speed of the roller 19 to allow for the proper spacing of the lengths of cork or the like cut off by the knife 22. If desired, however, the roller 14d may be driven intermittently.

In order to ensure accurate positioning of the assembled lengths in relation to the cork or like strip during the application of the latter, a grooved roller 23 is arranged above the roller 19 and driven in unison therewith by a train of gears 19j, 19k, 23a, 23b. The roller 23 is grooved to conform to the cigarette rod and is also formed 70 with a central peripheral groove 23c for the accommodation of a rubber felt or band 23d passing around a roller 23e arranged so that the belt or band 23d engages the assembled lengths and positions them centrally on the cork or like strip 75 while the latter is partially wrapped around the

lengths by the belt 20 passing into the garniture 21. The garniture 21 may be heated electrically or otherwise to assist setting of the adhesive and may have one or more seam-pressing rollers 21a or the equivalent associated therewith.

The wrapping belt 20 issuing from the garniture 21 passes over a roller 24 to a larger roller 25 driven through gears 26a, 25a from the main driving shaft 26 which is carried in bearings 53, 53a and thence is led around a roller 27, tensioning roller 28 mounted on a tension adjusting lever 28a controlled by a pawl 28b, and rollers 29, 30 to the roller 19.

The continuous composite rod issuing from the garniture 21 passes to a final cut-off apparatus 15 in which it is cut by a knife 31 (Fig. 1a) timed so as to bisect the lengths of cigarette rod and the double-filter tips to produce cigarettes each containing a length of tobacco and a filter tip or mouthpiece. For the purpose of enabling ready adjustment of the timing of the cut-off apparatus embodying the knife 31 and also the cork or like feed mechanism, such cut-off apparatus and feed mechanism are driven from the main shaft 26 through a differential gear train 25 permitting advance or retard in relation to the assembling means for the lengths of cigarette rod and double tips. For example, the cut-off apparatus may be driven from a vertical shaft 32 through bevel gearing 32a, 32b, such shaft 32 being geared by a bevel gear 32c to a double bevel wheel 28b which meshes with planetary bevel gears 28c mounted on a cross-pin or spider keyed to the main shaft 26 by pin 26'. The planetary gears 28c mesh with a bevel gear 33 loose on the shaft 26 and controlled manually through worm and worm wheel gearing 33a, 33b. The cork tip feed mechanism is preferably timed to the cut-off knife 31 by an inclined connecting shaft 34, and bevel gears 34a, 32d and 34b, 18c. By rotating the worm 33a the shaft 32 may, by the action of the differential gear train, be advanced or retarded in relation to the shaft 26, thereby varying the timing of the final cut-off and cork feed in relation to the assembling mechanism, 45 the main cross-shaft 13 of which is geared to the main shaft 26 by gears 13b (Figure 2), 13c, 26d. Such variation in timing causes axial displacement of the uniting band of cork or the like in relation to the assembled lengths and consequently by suitable operation of the differential gear train accurate registration may be readily obtained.

The stream of cigarettes or lengths of cigarette rod fed from the guide 1 may emanate from a 55 hopper feed or from transfer mechanism carrying cigarettes from cigarette-making machinery. Preferably, however, the stream issues directly from a continuous rod machine arranged in alignment with the guide 1 and having cut-off 60 means comprising a knife 35 (Fig. 1d) whereby the cigarette rod is cut into lengths and delivered into the guide 1, such cut-off means being driven from the main shaft 26 by a vertical shaft 35a and bevel gears 35b, 26e and 35c, 35d.

In starting up the machine it is desirable to avoid the feeding of lengths of cigarette rod into the guide 1 until the rod issuing from the continuous rod machine is properly packed and seamed, and further to be able to throw in the 70 feed to the guide 1 in timed relation to the knife 35. For this purpose a preliminary guide 36 associated with the inlet of the guide 1 is mounted or provided on a lever 36a (Figure 3) pivoted at 36b to a bracket 37. In starting up the machine 75

the lever 36a is held by an arm 38, mounted on a pivot 38a, engaging a part 36c on the lever 36a, so that the outer end of the lever provided with the guide 36 is maintained in a raised position in which the guide 36 is out of alignment with the guide 1. With the guide 36 in this position the lengths of cigarette rod as cut off fall freely away into a suitable receptacle. The arm 38 is provided with a roller 38b which, if the arm is moved away from the bracket 37 by pressing a knob 38d and thereby sliding the pivot 38a against a spring 38c, is brought into line with a cam 39 acting to throw the arm 38 out of engagement with the part 36c in timed relation to the knife 35, so that the guide 36 will be permitted to drop into alignment with the guide 1 to receive the leading length of cigarette rod from the knife 35. As soon as the feed of lengths of cigarette rod into the guide 1 is established, the knob 38d may be released so that the roller 38b again moves out of the path of the cam 39. The cam 39 is mounted on a spindle 39a driven from cut-off apparatus by a chain 40 engaging a sprocket 39b (Figs. 1d and 3). The lever 36a may be fitted with an adjustable stop 36d by which the alignment of the guide 36 with the guide 1 may be adjusted.

Any suitable means may be provided for charging the filter tips or double filter tips into the bores 4a in the disc or drum 4. In a preferred arrangement, adapted for use with sticks of wrapped filling, the length of which is a multiple of the length of filter tip, for example six, two transfer drums 41, 42 (Figs. 1c and 2) are provided, one extending at each side of the disc or drum 4, the drums 41, 42 having longitudinally extending channels 41a, 42a in their respective peripheries for the reception of the wrapped sticks of filling from hoppers 43, 44 respectively. Location of the wrapped sticks in the channels 41a, 42a is ensured by means such as a roller 44a (Figure 2) driven in the opposite direction to the travel of the transfer drums by means of a belt 44b passing around a pulley 45a on a shaft 45 geared to the shaft 13 by meshing spiral gears 45b, 13d. Fixed guides, such as 44c (Figure 2) are provided to retain the sticks in the channels 41a, 42a during their passage from the feed hoppers to the point of discharge. The drum 42 is driven intermittently by means of a cam wheel 46a on a shaft 46 geared to the shaft 45 by bevel gears 46b, 45c, such cam wheel 46a having teeth cooperating with a toothed wheel 42b and arranged to move the drum 42 through one step during six steps of movement of the disc or drum 4. The drum 41 is similarly driven by a cam wheel 47a co-operating with the toothed wheel 41b and mounted on a shaft 47 (Figure 1c) likewise driven by bevel gearing from the shaft 45.

Each drum 41, 42 is circumferentially slotted to accommodate rotary cutting discs 48 mounted on a spindle 48a carried by arms 48b and driven through gears 48c, 48d by a chain 49 passing over a sprocket 48e and guide sprockets 49a, 49b. The cutters 48 are arranged to subdivide the sticks into three parts and the intermittent drive to the drums 41, 42 is timed so that while one drum is stationary for the stage-by-stage ejection of the subdivided lengths of filling into the bores 4a in the disc or drum 4, the other drum is moved to bring a sub-divided stick into line with the ejecting means.

Ejection of the sub-divided sticks from the drum 42 is effected by a plunger 50 slidable in guides 50a, 50b (Figs. 1c and 1d), the forward movement of the plunger 50 being effected by

springs 50c under the control of a cam 45d (Figure 2) acting through a double-armed lever 50d. Lever 50d fulcrumed at 50e is provided with a slot 50f at the end opposite cam 45d in which a pin 50g carried by a block 50h is slidably mounted. Block 50h has a bore extending therethrough for plunger 50 which may be provided with a nut or other suitable means 50i on the free end thereof for preventing withdrawal of the plunger from said block by the action of spring 50c. The cam 45d being shaped so that the plunger 50 moves in steps to eject the sub-divided lengths from the respective channel 42a in the drum 42 one by one into the bores 4a, and so that after ejection of the three lengths the plunger 50 is withdrawn in one movement. Similarly, the ejection of the sub-divided lengths from the drum 41 is effected by a plunger 51 slidable in guides 51a, 51b and operated by springs 51c and a lever (not shown) co-operating with a cam on the shaft 45. Alternatively, or in addition, fixed guides 52 may be disposed to engage during rotation of drum 4 the projecting ends of any tips pushed too far through the drum to ensure the more or less central disposition of the double tips in the bores 4a.

It will be appreciated that owing to the use of sticks of filling each comprising three double length tips, the speed of the hopper feed and transfer drum mechanism is relatively slow with consequent advantages.

It will be understood that in operation the leading double length of cigarette rod issuing from the guide 1 is accelerated by engagement with the belt 3 passing over the roller 2 and is thereby butted against a double tip disposed in the bore 4a of the disc or drum 4 which is in alignment, thereby effecting the discharge of the double tip from the said bore. The double length of cigarette rod passing through the bore and the assembled lengths of cigarette rod and filter tip or mouthpiece formation or filling are again engaged by the belt 3 passing over the roller 5 and carried forward at the same speed into the garniture 7. At the same time the acceleration of the length of cigarette rod provides a space between it and the following length so that when the leading length of cigarette rod has passed through the bore 4a the following length is spaced at a sufficient distance to permit the intermittent movement of the disc or drum 4 to bring the next double tip into the space between the lengths 50 of cigarette rod. The butting of the pairs of assembled lengths together takes place in the guide tube 8 as it will be appreciated that the feed through such guide tube 8 is effected by the belt 3, if desired in conjunction with the feed roller 8a. In other words, abutting in tube 8 is effected by a length in engagement with belt 3 pushing a preceding length, not engaged by belt 3, through tube 8. In passing between the rollers 19 and 23, the assembled lengths are united by the application of the cork or like uniting bands by means such as described, and the continuous rod produced in passing through the garniture 21, which effects the wrapping of the uniting bands, and consisting of alternate lengths of cigarette rod and double filter tips, is finally cut off by the cutter 31.

It will be understood that the invention is not limited to the particular embodiment hereinbefore described. For example, a continuous stream of cigarettes which, if desired, may be shorter than normal, may be fed through the guide 1 and spaces may be formed therebetween to receive single length filter tips. In such a case the

cork or other uniting bands may be applied so as to unite the cigarettes and filter tips in pairs, in which case the final cut-off knife 31 is not required. Alternatively, the uniting bands may be 5 of suitable length and applied so as to unite the alternate cigarettes and filter tips together to form a continuous rod which may be cut off to provide cigarettes having a filter tip or other desired insertion at an intermediate position in its 10 length. In a further embodiment, cigarettes may be fed so that a space is formed between alternate pairs of cigarettes for the reception of a double length filter tip which is united to adjacent cigarettes by means of a uniting band and is subsequently bisected to provide cigarettes having 15 filter tip or like mouthpieces. Furthermore, any other suitable means may be provided for forming the spaces between the cigarettes or lengths of cigarette rod. Thus, if desired, the cigarettes 20 or lengths of cigarette rod may be fed into bores or chambers in an intermittently rotatable drum or the equivalent and carried thereby laterally into a position in alignment with filter tips or lengths of filling or insertion material, each cigarette or length of cigarette rod being ejected 25 axially as by means of a plunger, feed rollers or the like so as to butt the filter tip or the like and discharge the same axially on to a belt or the equivalent leading to the cork or other uniting 30 band-applying means. Alternatively, the filter tip or the like may be applied behind the laterally diverted cigarette or length of cigarette rod. In such modified arrangements the axial ejection of the assembled lengths will be effected at a suitably increased speed in order to permit the association of the filter tips or double filter tips between alternate cigarettes or lengths of cigarette 35 rod. Furthermore, non-wrapped filter tips or double filter tips may be utilised by providing 40 means for transferring the same directly or indirectly from forming mechanism associated with the length-assembling means. The invention is applicable to the production of cigarettes provided with filter tips or like fillings of any suitable 45 material and formation, including fillings consisting wholly or in part of tobacco, and also to the production of cigarettes provided with tubular or like mouthpieces or insertions.

In all embodiments spaces may be formed 50 between cigarettes or lengths of cigarette rod in the manner described and the lengths of filter tip or other filling or insertion may be applied into the spaces subsequently at any position in advance of the uniting band-applying means.

55 What we claim is:

1. A method of producing composite cigarettes, wherein cigarettes or lengths of cigarette rod fed in a continuous stream are accelerated to form spaces permitting the assembly of lengths of insertion in line with the cigarettes or lengths of cigarette rod and to cause the latter to butt against the lengths of insertion, and wherein, during the continued forward travel of the assembled lengths butted one against the other, bands of external tipping material are applied 60 to unite the same.

2. A method of producing composite cigarettes on the continuous rod principle, which comprises cutting a continuous cigarette rod into suitable 65 lengths, accelerating each length after it is cut off to provide a space behind the same permitting the application of a length of insertion in line with the length of cigarette rod, and to cause the latter to butt against a length of insertion so applied, and uniting the butted lengths of cigarette 70

rod and of insertion by means of bands of external tipping material.

3. Apparatus for the production of filter tip or composite cigarettes, comprising means for feeding cigarettes or lengths of cigarette rod in a continuous stream, an intermittently movable rotary member arranged with its axis parallel to the direction of feed of the continuous stream and having a circumferential series of bores, mechanism for inserting lengths of insertion into the 10 said bores, means disposed adjacent the said rotary member and adapted to engage the lengths of cigarette rod successively and to accelerate the same through the bore in the rotary member which at the moment is in alignment, a belt for carrying the assembled lengths of insertion and lengths of cigarette rod into and through a guide, mechanism associated with the outlet from the 15 said guide and adapted to apply uniting bands of material to the assembled lengths, and means for wrapping the uniting bands around the assembled lengths during their continued forward movement.

4. Apparatus for the production of composite cigarettes, comprising means adapted to assemble 20 lengths of insertion in line with cigarettes or lengths of cigarette rod, and mechanism arranged to apply bands of material to unit the assembled lengths while moving axially, said band-applying mechanism comprising a cutter, a belt and suction box for directing a strip of material to said cutter, a rotary element for receiving lengths of said strip of material cut off by said cutter, suction means on said rotary element for retaining 25 said lengths of material until positioned in engagement with the lengths of cigarette rod, a wrapping belt associated with said rotary element, a garniture associated with said belt for wrapping the lengths of material about the 30 lengths of cigarette rod, a grooved roller provided immediately above said rotary element, and a belt carried by said grooved roller and extending along the path of travel of the lengths of cigarette rod for engaging the assembled lengths during wrapping.

5. An apparatus for the production of composite cigarettes, comprising means for feeding cigarettes or lengths of cigarette rod in a continuous stream, means for accelerating the lengths to form a space between adjacent cigarettes or lengths of cigarette rod, an intermittently movable rotary insertion carrier mounted for rotation about an axis parallel to the direction of movement of said stream of cigarettes or lengths of cigarette rod for inserting 50 lengths of insertion in said space in line with the cigarettes or lengths of cigarette rod, and means for applying bands of uniting material about juxtaposed lengths to unite said lengths.

6. An apparatus for the production of composite cigarettes, comprising means for feeding cigarettes or lengths of cigarette rod in a continuous stream, means for accelerating the lengths to form a space between adjacent cigarettes or lengths of cigarette rod, an intermittently movable rotary insertion carrier mounted for rotation about an axis parallel to the direction of movement of said stream of cigarettes or lengths of cigarette rod, said carrier having a circumferential series of bores parallel to the axis 60 thereof for bringing insertions carried in said bores into alignment with the cigarettes or lengths of cigarette rod in the space provided between the adjacent cigarettes or lengths of cigarette rod, and means for applying bands of unit- 65

ing material about juxtaposed lengths to unite said lengths.

7. In an apparatus of the character described, means for feeding a stream of cigarettes or cigarette rod lengths, a pair of cooperating rollers for accelerating the first length of said stream away from the following lengths of said stream, means for positioning an insertion in front of said first length to be abutted by and displaced by said length, and a second pair of cooperating rollers moving at the same speed as the first-mentioned accelerating rollers for receiving the abutted length and insertion and displacing them away from the insertion positioning means.

15. 8. In an apparatus of the character described, means for feeding a stream of cigarettes or cigarette rod lengths, a pair of cooperating rollers for accelerating the first length of said stream away from the following lengths of said stream, means for positioning an insertion in front of said first length to be abutted by and displaced by said length, a second pair of cooperating rollers moving at the same speed as the first-mentioned accelerating rollers, and a belt passing over one of said second pair of rollers for receiving the abutted length and insertion and displacing them away from the insertion positioning means.

9. In an apparatus of the character described, means for feeding a stream of cigarettes or cigarette rod lengths, a pair of cooperating rollers for accelerating the first length of said stream away from the following lengths of said stream, means for positioning an insertion in front of said first length to be abutted by and displaced by said length, a second pair of cooperating rollers moving at the same speed as the first-mentioned accelerating rollers, a guide tube, and a belt passing over one of said second pair of rollers for receiving the abutted length and insertion and displacing them into said guide tube into abutting relation with a preceding abutted length and insertion.

40 10. In an apparatus of the character described, a rotary insertion carrier for positioning insertions in a stream of cigarettes or cigarette rod lengths, means for imparting intermittent rotary motion to said carrier, duplicate feed hoppers for supplying insertions to said carrier, and transfer mechanisms on opposite sides of said carrier for alternately feeding insertions to said carrier from opposite sides.

45 11. In an apparatus of the character described, a rotary insertion carrier for positioning insertions in a stream of cigarettes or cigarette rod lengths, means for imparting intermittent rotary motion to said carrier, a feed hopper for supplying insertions to said carrier, means including a rotary transfer member for transferring insertions from said hopper to said carrier, and means for imparting intermittent rotary motion to said transfer member.

50 12. In an apparatus of the character described, a rotary insertion carrier for positioning insertions in a stream of cigarettes or cigarette rod lengths, means for imparting intermittent rotary motion to said carrier, a feed hopper for supplying insertions to said carrier, a rotary transfer member for transferring insertions from said hopper to said carrier, means for imparting intermittent rotary motion to said transfer member, said carrier and transfer member having bores for receiving the insertions, one bore of the carrier registering with one bore of the transfer member in the stationary position of said carrier and transfer member, and means for

axially displacing an insertion from a bore in the transfer member into a registering bore of the carrier.

5 13. In an apparatus of the character described, a rotary insertion carrier for positioning insertions in a stream of cigarettes or cigarette rod lengths, means for imparting intermittent rotary motion to said carrier, a feed hopper for supplying insertions to said carrier, a rotary transfer member for transferring insertions from said hopper to said carrier, means for imparting intermittent rotary motion to said transfer member, said carrier and transfer member having bores for receiving the insertions, one bore of the carrier registering with one bore of the transfer member in the stationary position of said carrier and transfer member, means for subdividing multiple length insertions while in the bores of said transfer member, and means for axially displacing the subdivided insertions from a bore in the transfer member in stages into registering bores of the carrier.

line, and external tip-applying mechanism arranged to unite the assembled lengths by the application of uniting bands after said lengths have been butted together, the said means adapted to accelerate the lengths comprising a pair of cooperating rollers arranged in advance of the position at which the lengths of insertion are applied and cooperating rollers arranged beyond the position at which the lengths of insertion are applied.

18. Apparatus for the production of composite cigarettes, comprising means adapted to assemble lengths of insertion in line with cigarettes or lengths of cigarette rod, mechanism arranged to apply bands of material to unite the assembled lengths while moving axially and a garniture and tubular guide member in which butting of the assembled lengths takes place to lead the assembled lengths to the means for applying the uniting bands.

19. Apparatus for the production on the continuous rod principle of composite cigarettes, comprising cutting means adapted to sever a continuous cigarette rod into suitable lengths, means adapted to engage and to accelerate the lengths to provide intermediate spaces at predetermined positions, a tubular guide for guiding the lengths to the accelerating means, mechanism for depositing lengths of insertion in the said spaces to effect assembly of the lengths in line, means adapted to apply bands of external tipping material in such manner as to unite the assembled lengths after they are butted together, and means for throwing in the feed of cigarettes or lengths of cigarette rod to said guide in timed relation to the cutting means for severing the cigarette rod into lengths.

20. Apparatus as claimed in claim 19, where-

in the means for throwing in the feed of cigarettes or lengths of cigarette rod comprise a preliminary guide, a pivoted arm or lever carrying said preliminary guide, an arm or catch for holding said pivoted arm or lever initially in a raised position, and a cam operating in timed relation to the cut-off mechanism associated with the continuous rod machine and arranged so that on bringing the arm or catch into line with the cam the latter acts upon the arm or catch so as to disengage the arm or lever carrying the preliminary guide and allow the latter to move into position to receive the cigarettes or lengths of cigarette rod as cut off and direct them into the guide leading to the assembling means.

21. Apparatus for the production of composite cigarettes, comprising means for feeding cigarettes or lengths of cigarette rod in a continuous stream, means adapted to accelerate the lengths in such manner as to form intermediate spaces at a predetermined position, means adapted to transfer lengths of insertion into the said spaces to effect the assembly of the lengths in line, and external tip-applying mechanism arranged to unite the assembled lengths by the application of uniting bands after said lengths have been butted together, said means adapted to accelerate the lengths comprising a pair of cooperating rollers arranged in advance of the position at which the lengths of insertion are applied, cooperating rollers arranged beyond the position at which the lengths of insertion are applied, and a belt passing over one roller of the first pair and over one roller of the second pair.
